UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

PRINTING-PLATE-SHAVING MACHINE.

1,126,344.

Specification of Letters Patent. Patented Jan. 26, 1915.

Original application filed June 21, 1909, Serial No. 508,866. Divided and this application filed October 31, 1910. Serial No. 589,995.

To all whom it may concern:

Be it known that I, HOWARD M. BARBER, a citizen of the United States, and resident of Stonington, in the county of New London and State of Connecticut, have invented a new and useful Improvement in Printing-Plate-Shaving Machines, of which the following is a specification.

- The objects of my invention are to provide certain novel features in the construction, form and arrangement of the several parts of a printing plate shaving machine whereby a stop is provided for limiting the downward movement of the knife; an accurate adjusting means is provided for the knife and in which all lost motion in the knife head is obviated thus insuring a shaving of the printing plate with the utmost accuracy.
- In the accompanying drawings, Figure 1 represents the shaving machine in side elevation, the several parts being shown in full lines in the position which they assume when the machine is at rest with the reciprocating bed at the limit of its forward movement and in dotted lines when the reciprocating bed is at the limit of its rearward movement, Fig. 2 is a top plan view of the same, Fig. 3 is a front end view of the machine, Fig. 4 is a detail view showing more clearly the brake for stopping the reciprocating bed at the limits of its movement, Fig. 5 is a section taken in the plane of the line A—A of Fig. 4, looking in the direction of the arrows, Fig. 6 is an enlarged detail longitudinal vertical section, Fig. 7 is a detail transverse section through a portion of the machine showing one of the plate pressure rolls, Fig. 8 is a fragmentary horizontal section taken in the plane of the line B—B of Fig. 6, looking in the direction of the arrows, Fig. 9 is a detail transverse section taken in the plane of the line C—C of Fig. 6, looking in the direction of the arrows, and Fig. 10 is a detail plan view partially in section showing the connections for automatically applying the brake to limit the backward and forward movements of the bed.
- The bed frame of the machine is denoted by 1 and its supporting legs by 2. The bed frame is provided with ways 3, for guiding the reciprocating bed 4 in its forward and rearward movements. The reciprocating

bed 4 is provided with a rack 5, which 55 rack is engaged by a reversing pinion 6 fixed to a cross shaft 7 suitably mounted in the bed frame 1. This cross shaft 7 is driven by a worm and gear connection 8, 9, from a drive shaft 10, which shaft is in turn 60 driven from any suitable source of power such, for instance, as a reversing motor 11, by a belt and pulley connection 12, 13, 14.

A motor controlling lever 15 is fixed to a cross rock shaft 16 supported by suitable 65 hangers 17 from longitudinal tie rods 18 carried by the legs 2 of the framing. The motor controlling lever 15 is arranged to control the direction of movement of the motor shaft 19 through a controller 20 of 70 any suitable design, the pinion 21 of which controller meshes with the teeth of a rack bar 22 connected to the lever 15.

It is to be understood that in the arrangement of the parts as herein shown, when 75 the lever is swung forwardly the motor shaft will be driven in a direction to cause the reversing pinion 6 to drive the reciprocating bed rearwardly; when the lever is moved rearwardly the motor shaft will be 80 driven in the reverse direction to cause the pinion 6 to drive the bed forwardly, and when the lever is in its intermediate position the controller will be in its neutral position and the movement of the motor 85 shaft stopped.

The shaving knife is denoted by 23 and it is adjustable by means of screws 26 and clamped in its adjustments by means of set screws 25 upon a member 24 of the vertically movable knife carrying head 27, which head is suitably mounted between the uprising sides 28 of the bed frame 1. The member 24 of the knife carrying head 27 is in turn adjustably mounted upon the said 90 knife carrying head as follows: An approximate adjustment of this knife carrying member 24 is provided for by means of vertical adjusting screws 29, 30, rotatably mounted in the knife carrying head 27, which screws 95 pass through interiorly threaded lugs 31, 32, projecting from the member 24 through vertically elongated recesses 33, 34, in the knife carrying head 27. Coil springs 35, 36, surround the screws 29, 30, and are interposed between the bottoms of the recesses 33, 34, and the lugs 31, 32, respectively, for eliminating all lost motion be-

tween the said lugs and screws. These screws 29, 30, are provided with spur gears 37, 38, which mesh with a spur gear 39 fixed to the shaft 40 of a hand wheel 41 mounted on the knife carrying head 27.

A micrometer adjustment of the knife carrying member 24 is provided for through a worm 42 carried by a horizontal hand shaft 43 mounted on the knife carrying head

10 27, which worm may be moved into and out of mesh with a worm gear 44 fixed on the shaft 40 of the hand wheel 41. In the present instance, a hand lever 45 is provided for this purpose.

15 The crank handle of the shaft 43 is denoted 46.

A suitable disk scale 47 may be provided on the shaft 40 for accurately adjusting the vertical position of the knife with respect

20 to the knife carrying head to a predetermined point. The knife is clamped rigidly to the knife carrying head in its predetermined vertical adjustment by providing screw bolts 48 which enter the rear ends of 25 the lugs 31, 32, between the heads of which bolts and the back face of the head 27 are interposed clamping plates 49. Vertical slots 50, 51, are provided through the rear wall of the recesses 33, 34, into which the 30 rear ends of the lugs 31, 32, extend.

The knife carrying head 27 is moved toward and away from the traveling bed by the following means: A rock shaft 52 is mounted in the bed frame 1 and beyond the 35 bed frame upon both sides of the machine the shaft is provided with eccentric portions 53, 54, journaled in boxes 55, 56, which rest upon the horizontal bottom walls of the loops 57, 58, of frames 59, 60, secured to

40 the opposite ends of the knife carrying head 27 as, for instance, by screw bolts 61, 62. The lower ends of these loop frames 59, 60, are guided by pins 63, 64, supported in brackets 65, 66, projecting from the bed

45 frame 1. The knife carrying head 27 is pressed upwardly under the strong tension of springs 67, 68, which also serve to hold the horizontal bottom walls of the loops 57, 58, of the frames 59, 60, snugly in en-

50 gagement with the boxes 55, 56, carried by the eccentric portions 53, 54, of the cross rock shaft 52. Upon one side of the machine an operating lever 69 for manually raising the knife carrying head at any time in the 55 rearward movement of the bed, is fixed to a concentric pin 70 extending outwardly from the eccentric portion 54 of the shaft 52.

The means for automatically controlling the raising and lowering of the knife carrying head by the movement of the reciprocating bed so that the shaving knife will be lowered before the bed starts on its rearward movement and raised before the bed starts on its forward movement, is constructed, and arranged as follows: On the

side of the machine upon which the levers 15 and 69 are located, the reciprocating bed 4 is provided with a fixed abutment 71 at its forward end and a longitudinally adjustable abutment 72 near its rear end, the 70 adjustment of which abutment 72 is provided for in the present instance by a removable pin 73 arranged to engage any one of a series of holes 74 along the side of the reciprocating bed 4. As the reciprocating 75 bed 4 approaches the limit of its rearward movement, the front abutment 71 will engage the free end of an arm 75 mounted upon a stud shaft 76 carried by the bed frame 1. When the reciprocating bed 4 approaches the limit of its forward movement, the abutment 72 will engage an arm 77 carried by a hub 78 mounted upon a stud shaft 79. A link bar 80 connects the arms 75 and 77 so that these two arms are moved together. The hub 78 is further provided with an arm 81 which is connected to an arm 82 on the hub of the lever 69 by a connecting link 83 so that the shaft 52 is rocked by the 85 rocking movement of the arms 75 and 77 for automatically raising and lowering the knife carrying head. The lever 15 is connected to the arm 75 by a lost motion connecting link 84, which link has a pin and slot connection 85, 86, with the said lever 15. 90 This lost motion connection between the controlling lever 15 and the arm 75 permits the operator to throw the controlling lever 15 into its neutral position at any time during the rearward movement of the reciprocating bed 4 whenever the lever 69 is raised by hand for manually lifting the knife carrying head.

The rearward and forward movements of the bed are stopped by a brake mechanism under the control of the bed as follows: A band brake is located on the shaft 10, the brake drum being denoted by 87 and the brake band by 88. The band tightening lever is denoted by 89 and it is engaged by a 105 double cam 90 carried by an arm 91 fixed to a cross rock shaft 92 mounted in the bed frame 1 at the rear end of the machine. This shaft 92 is provided with a depending arm 93 which is connected by a link rod 94 with an uprising arm 95, fixed to the rock shaft 16 upon which the controlling lever 15 is also fixed. This arm 95 is located at the opposite side of the machine from the lever 15 and it is provided 115 with a rearwardly extended bar 96 resting in suitable guides 97, 98, on the bed frame 1, along the side of the reciprocating bed 4. This bar 96 is provided with uprising lugs 99, 100. The reciprocating bed 4 is provided with a front fixed abutment 101 corresponding to the abutment 71 and a longitudinally adjustable rear abutment 102 corresponding to the abutment 72. This rear abutment 102 is shown as a pin which may 120

be inserted through any one of a series of holes 103 located along the side of the reciprocating bed 4. These abutments 101, 102, are so placed that they will engage the 5 uprising lugs 99, 100, respectively, of the rearwardly extended bar 96 for moving the several arms and levers to apply the brake to stop the movement of the bed and for throwing the controlling lever 15 into its 10 neutral position to stop the operation of the motor, as will hereinafter appear in descriptions of the operation of the machine.

Suitable spring pressed rollers 104, 105, are arranged to the front and rear of the 15 cutting edge of the shaving knife 23 in position to exert their pressure upon the back of the printing plate being shaved. Each of these rollers 104, 105, is provided with shanks 106, 107, extending upwardly through 20 the knife carrying member 24, springs 108, 109, being provided for yieldingly holding the rollers at the limit of their downward movement and adjusting nuts 110, 111, being provided for adjustably limiting the 25 downward movement of the said rollers. The downward movement of the knife carrying head 27 is limited by vertically adjustable bolts 112 which have screw threaded engagements with lugs 113 on the 30 rising sides 28 of the bed frame 1, the heads of which bolts are adjusted into position to be engaged by the under side of a rearwardly extended shelf 114 of the knife carrying head as the head reaches approximately 35 its lowest position, thus rigidly supporting the head in its lowered position during the shaving operation. Lock nuts 115 on the bolts 112 serve to lock the bolts in their proper adjusted position with respect 40 to the knife carrying head.

In operation, supposing the parts to be in the position shown in full lines, Fig. 1, with the reciprocating bed at the limit of its forward movement, the controlling lever 45 15 in its neutral position and the band brake applied and the motor at rest: The controlling lever 15 is swung forwardly into the position indicated by the line X—X, Fig. 1, the slot 86 in the link bar 84 permitting the 50 lever 15 to be swung into this position without affecting the knife carrying head operating mechanism. This forward movement of the lever 15 will release the brake and, at the same time, start the motor. The bed 55 will travel rearwardly underneath the shaving knife and as it approaches the limit of its rearward movement, its abutment 101 will engage the lug 99 of the bar 96 thus rocking the arm 95 in a direction to move 60 the cam 90 into position to apply the brake 87, 88, 89. This same rocking movement of the arm 95 will rock the shaft 16 a sufficient distance to swing the controlling lever 15 rearwardly into its neutral position, thus 65 stopping the motor. Furthermore, as the

reciprocating bed nears the limit of its rearward movement, the front stop 71 thereon will engage the arm 75 and move it rearwardly a sufficient distance to rock the shaft 52 for causing its eccentric portions 53, 54, 70 to move upwardly to permit the springs 67, 68, to lift the knife carrying head 27 away from the reciprocating bed 4. If, at any time during the rearward movement of the bed 4, it is desired to stop the shaving operation, 75 the lever 69 can be raised by hand thus permitting the spring 67, 68, to lift the knife carrying head and through the link connection 84 swing the controlling lever 15 into its intermediate position to stop the motor. 80 After the reciprocating bed reaches the limit of its rearward movement and the knife carrying head is raised, the controlling lever 15 may be moved rearwardly into the position indicated by the line Y—Y of Fig. 1, 85 thus releasing the brake and reversing the motor. As the bed approaches the limit of its forward movement, the abutment 102 will engage the lug 100 of the bar 96 and swing the uprising arm 95 forwardly a sufficient distance to move the double faced cam 90 into position to apply the brake. This movement of the arm 95 will also rock the shaft 16 a sufficient distance to move the 90 controlling lever 15 into its intermediate 95 position, thus stopping the motor.

By the construction, form and arrangement of the several parts, as herein shown and described, it will be seen that by providing a positive limit for the downward movement of the knife carrying head and providing springs for raising the same, the head will be held rigidly against movement when in its lowered position during the 100 shaving operation, thus permitting the adjustment of the knife carrying member with the utmost accuracy. Furthermore, by providing the springs 35, 36, around the adjusting screws 29, 30, all lost motion is taken up at this point and a micrometer adjustment of the knife carrying member may be obtained after an approximate adjustment thereof has been obtained. It will furthermore be seen that both an automatic means 105 is provided for raising the knife carrying head and a manually operated means is provided for obtaining this movement.

The parts shown and described but not claimed herein, which relate to the control of the brake and the motor by the reciprocating bed; the automatic raising and lowering of the knife and the automatic stopping of the motor at any desired point in the rearward movement of the bed, form the 110 subject matter of my co-pending application filed July 21, 1909, serial No. 508866, of which this is a division.

What I claim is:—

1. In a machine of the character described, a knife carrying head, a reciprocating

ing bed, a stop for limiting the downward movement of the head, springs tending to move the head away from the stop and means controlled by the bed for automatically bringing the head down into rigid engagement with the stop as the bed reaches a predetermined point in its movement.

2. In a machine of the character described, a knife carrying head, a knife carrying member, means for adjusting the knife carrying member approximately, a micrometer adjusting device for the knife carrying member and means for rendering the micrometer adjusting device operative

10 and inoperative with respect to said knife carrying member.

3. In a machine of the character described, a knife carrying head, a knife carrying member, means for adjusting the knife carrying member approximately, a micrometer adjusting device for the knife carrying member, means for rendering the micrometer adjusting device operative and inoperative with respect to said knife carrying member.

20 4. In a machine of the character described, a knife carrying head, a knife carrying member approximately, a micrometer adjusting device for the knife carrying member, means for rendering the micrometer adjusting device operative and inoperative with respect to said knife carrying member and means for locking the knife carrying member in its adjusted position.

25 5. In a machine of the character described, a knife carrying head, a knife carrying member, adjusting screws carried by the head engaging the member and springs arranged in position to prevent lost motion between the adjusting screws and knife carrying member.

30 6. In a machine of the character described, a knife carrying head, a knife carrying member, and a rock shaft having eccentric portions connected to the head for drawing the head downwardly as the shaft is rocked in one direction and permitting the head to lift as the shaft is rocked in the opposite direction.

40 7. In a machine of the character described, a knife carrying head, a knife carrying member, means for adjusting the knife carrying member approximately, a micrometer adjusting device including a worm and worm gear, and means for moving the worm and worm gear into and out of engagement to render the micrometer adjusting device operative and inoperative with respect to said knife carrying member.

45 8. In a machine of the character described, a knife carrying head, a knife carrying member, means for adjusting the knife carrying member approximately, a micrometer adjusting device including a worm and worm gear, means for moving the worm and worm gear into and out of engagement to render the micrometer adjusting device operative and inoperative with respect to said knife carrying member.

50 9. In a machine of the character described, a knife carrying head, a knife carrying member, means for adjusting the knife carrying member approximately, a micrometer adjusting device including a worm and worm gear, means for moving the worm and worm gear into and out of engagement to render the micrometer adjusting device operative and inoperative with respect to said knife carrying member, and means for locking the knife carrying member in its adjusted position.

55 In testimony, that I claim the foregoing as my invention, I have signed my name in presence of two witnesses, this 26th day of October, 1910.

HOWARD M. BARBER.
